UNITED STATES PATENT OFFICE.

GEORGE SCHWIBINGER, OF MILWAUKEE, WISCONSIN, ASSIGNOR TO RUNDLE-SPENCE MANUFACTURING COMPANY, OF MILWAUKEE, WISCONSIN, A CORPORATION OF WISCONSIN.

AUTOMATIC FLUSHING MECHANISM FOR CLOSETS.

1,157,187.

Specification of Letters Patent.

Patented Oct. 19, 1915.

Application filed April 19, 1915. Serial No. 22,349.

To all whom it may concern:

Be it known that I, GEORGE SCHWIBINGER, a citizen of the United States, residing at the city of Milwaukee, county of Milwaukee, 5 and State of Wisconsin, have invented new and useful Improvements in Automatic Flushing Mechanism for Closets, of which the following is a specification.

My invention relates to improvements in 10 flushing mechanism for water closets, and it pertains more especially to the device for temporarily holding the outlet discharge valve of a water closet in its raised position and for automatically releasing such valve 15 by the descent of a float as the water in such closet escapes past said valve. Said device for thus holding and releasing the outlet valve of a water closet being shown in Figures 2 and 3 of the drawings forming a part 20 of application for Letters Patent Serial No. 570,040, filed by me July 2, 1910. The claims of said pending application being limited to the seat actuated mechanism for raising said valve.

25 My invention is further explained by reference to the accompanying drawings, in which—

Fig. 1 represents a side view of a closet in connection with an elevated water tank provided with my improved flushing mechanism. Fig. 2 is a vertical section of the tank showing a side view of the valve mechanism therein. Fig. 3 is a vertical section of said flushing tank drawn at right angles to that 35 shown in Fig. 2, and Fig. 4 is a detail, part in vertical section, of the device for communicating motion from the closet seat to the valve operating mechanism.

Like parts are identified by the same reference numerals throughout the several 40 views.

It will be understood that the closet bowl 1, the water closet cistern 2, duct 3, inlet water duct 4, valve mechanism 5, float 6, 45 duct 7, lever 8, the mechanism for communicating motion from the float 6 through the lever 8 to the valve 5, and siphon duct 9 communicating from near the bottom of the closet cistern 2 with the upper end of the 50 duct 3, are all substantially of ordinary construction and need not for such reason be

herein more specifically described; while the mechanism for communicating motion from the slidable member 16' to the two armed lever 25 forms the subject matter of my said 55 pending application, invention herein being predicated, more especially, upon the mechanism for temporarily supporting the valve 26 in its raised position as indicated by dotted lines in Fig. 3 and for automatically releasing said valve as the water escapes from the water closet cistern 2.

10 represents the seat of the closet which is rigidly connected with the operating lever 11, and said operating lever 11 is connected 65 with the closet through the bracket 12 and pivotal bolt 13. The lever 11 is also pivotally connected with the vertical moving rod 14' through the bracket 15 and pivotal bolt 16 and the upper end of the rod 14 is rigidly 70 affixed to the slidable member 16' by the bearing 17, and said member 16' is slidably supported from the tank within a sleeve 18. 19 is a block which is rigidly affixed to the rod 14'. 20 is a spring which is interposed 75 between the upper end of the block 19 and the lower side of the sleeve 18, whereby as the rod 14 is raised by downward pressure upon the seat said spring will be compressed and whereby the swinging member 21, which 80 is pivotally connected to the member 16', will be raised above the short arm 24 of the lever 25. As soon, however, as the pressure upon the seat is removed said rods 14 and 14' will be forced down by the recoil of said 85 spring.

Motion is communicated from the slidable member 16' to the flushing valve 26 through the swinging member 21, lever 25 and links 28 and 29. The member 21 is pivotally supported from said slidable member 16 on the bolt 22.

It will now be understood that when downward pressure is applied to the seat an upward movement will be communicated to 95 the member 21 through the intermediate mechanism described, whereby the lower end 23 of the member 21 will be raised and caused to swing above the short arm 24 of the lever 25, whereby as soon as the downward pressure upon the seat is relieved the member 21 will be brought into contact with 100

the short arm 24 of the lever 25, said short arm will be forced down by the recoil of said spring 20 acting through the intermediate parts, whereby the flushing valve 26 will be raised when water will escape from the tank through the outlet duct 3 to the closet. The member 21 is provided with a rearward extending lug 21', indicated by dotted lines in Fig. 2, which is adapted to bear against the right hand side of the sleeve 18, reference being had to Fig. 2 of the drawings, whereby said member 21 is prevented from swinging too far toward the left when it is moved downwardly in contact with the short arm 24 of the lever 25. The valve 26 may be raised by the downward movement of the seat 10 or it may be otherwise raised by a direct upward pull of the operator upon the rod 29. As the rod 29 is moved upward the angular stop 31 is brought in contact with the beveled end of the latch 30. The latch 30 is pivotally supported from the side of the arm 34 by the pivotal bolt 35. It will now be obvious that when the stop 31 has been drawn past the upper surface of the latch 30 the valve 26, which is connected with said stop 31 by the rod 29, will be retained in its raised position until the water has escaped from the water closet cistern 2. When the water has descended from the water closet cistern 2 to or past the float 32 the float 32 will thereafter descend with the water, whereby the latch 30, which is connected with said float through the arm 34 and pivotal bolt 35, will be withdrawn from beneath the stop 31 when the valve 26 will drop back to its seat, whereby the further escape of water from the water closet cistern 2 will be prevented. It will, of course, be understood that so long as the water remains in the water closet cistern 2 the float 32 will be buoyed up and retained in its elevated position, whereby the latch 30 will remain beneath the stop 31 and the valve 26 will remain open. When, however, the contents of the tank 2 have been discharged said latch 30 will be withdrawn from the stop by the downward movement of the float 32, thus permitting said valve 26 to close, as stated, when it remains in its closed position until again raised by the act of the user.

36 is a bracket which is rigidly connected at one end to one leg of the siphon 9 in any convenient manner. The bracket 36 is preferably formed of two parts, the outer end 37 of which is provided with an aperture for the reception of the valve rod 37', whereby said bracket serves as a guide to said guide rod. The parts 36 and 37 are pivotally connected together by the adjustable screw 38, which passes through the joint 39 of said bracket. The lower end of the screw 38 serves as a stop to limit the upward move-

ment of the valve 26, while it also serves the additional purpose of connecting the two members of said bracket together.

Having thus described my invention what I claim as new and desire to secure by Letters Patent, is:—

1. In a device of the described class, the combination with a water closet cistern having a discharge valve, of a valve rod, a conical stop affixed to said rod, a bracket rigidly supported above said valve, a float, a float supporting rod pivotally connected at one end with said bracket, a latch hinged at one end to said float rod and adapted to bear at its opposite end against said conical stop, the free end of said latch being adapted to be raised by contact with said conical stop as the latter is raised, and to drop back beneath said stop as the latter passes said latch, said latch being adapted when beneath said conical stop to retain said valve in its open position, whereby the float supporting water is permitted to escape and said float to descend, whereby said latch is withdrawn from beneath said stop when said valve will again drop to its seat.

2. In a device of the described class, the combination with a water closet cistern having a discharge valve, of a valve rod, a conical stop affixed to said rod, a bracket rigidly supported above said valve, a float, a float supporting rod pivotally connected at one end with said bracket, said bracket being provided with an aperture for the reception of said valve rod, a latch hinged at one end to said float rod and adapted to bear at its opposite end against said conical stop, the free end of said latch being adapted to be raised by contact with said conical stop as the latter is raised, and to drop back beneath said stop as the latter passes said latch, said latch being adapted when beneath said conical stop to retain said valve in its open position, whereby the float supporting water is permitted to escape and said float to descend, whereby said latch is withdrawn from beneath said stop when said valve will again drop to its seat.

3. In a device of the described class, the combination with a water closet cistern having a discharge valve, of a valve rod, a conical stop affixed to said rod, a bracket rigidly supported above said valve, a float, a float supporting rod pivotally connected at one end with said bracket, said bracket being provided with an aperture for the reception of said valve rod, said bracket being formed of two members adjustably connected together, an adjustable screw having threaded bearings in said bracket and adapted to serve as a stop to limit the upward movement of said valve, a latch pivotally connected at one end to said float rod and adapted to bear at its opposite end against said conical stop,

the free end of said latch being adapted to be raised by contact with said conical stop as the latter is raised, and to drop back beneath said stop as the latter passes said latch, said latch being adapted when beneath said conical stop to retain said valve in its open position, whereby the float supporting water is permitted to escape and said float to descend, whereby said latch is withdrawn

from beneath said stop when said valve will again drop to its seat.

In testimony whereof I affix my signature in the presence of two witnesses.

GEORGE SCHWIBINGER.
